Patented Dec. 6, 1921.

Inv. & Atty.
Frederick Wehinger
Sigmund Earle

UNITED STATES PATENT OFFICE.

FREDERICK WEHINGER, OF WATERBURY, CONNECTICUT, ASSIGNOR TO WATERBURY CLOCK CO., OF WATERBURY, CONNECTICUT, A CORPORATION.

CHIME AND STRIKE CLOCK MOVEMENT.

1,399,452.

Specification of Letters Patent.

Patented Dec. 6, 1921.

Application filed September 29, 1921. Serial No. 504,191.

To all whom it may concern:

Be it known that I, FREDERICK WEHINGER, a citizen of the United States, residing at Waterbury, in the county of New Haven and 5 State of Connecticut, have invented a new and useful Improvement in Chime and Strike Clock Movements; and I do hereby declare the following, when taken in connection with the accompanying drawings and 10 the characters of reference marked therein, to be a full, clear, and exact description of the same, and which said drawings constitute part of this application, and represent, in—

15 Figure 1 a broken view in rear elevation of the upper portion of a clock-movement embodying my improvement, with the converting means assembled as for a relatively large dial.

20 Fig. 2 a plan view thereof.

Fig. 3 a view corresponding to Fig. 1, but showing the converting means assembled as for use with a smaller dial.

25 Fig. 4 a detached view in elevation of one of the two auxiliary plates.

Fig. 5 a detached view in elevation of the chime-cut-out-lever.

Fig. 6 a corresponding view of the regulator-lever.

30 My invention relates to an improvement in chime and strike clock-movements, the object being to adapt a movement of given size to be readily converted for use with dials laid out to have their chime-cut-out- 35 arbor holes and their regulator-arbor holes located at different distances from their center arbor-holes.

With these ends in view, my invention 40 consists in a clock-movement having certain details of construction and combinations of parts as will be hereinafter described and pointed out in the claims.

45 In carrying out my invention, as herein shown, I employ two complementary, auxiliary plates 10 and 11, secured at their ends by screws 12 to the upper corners of the rear and front movement-plates 13 and 14, above which the said auxiliary plates extend. Each of the auxiliary plates is provided with 50 an upper and a lower pair of bearing-holes 15, the holes of the lower pair being nearer together than the holes of the upper pair, and the holes in the rear plate being larger than the holes in the front plate to provide

for the mounting of the friction-bushings 16, 55 which provide bearings for the regulator-arbor 17 and the chime-cut-out-arbor 18, the forward ends of which bear, as the case may be, in the upper or lower pair of holes 15 in the front auxiliary plate. As shown in Figs. 60 1 and 2, the said arbors are mounted in the upper pair of bearing-holes in the said auxiliary plates, while in Fig. 3 they are mounted in the holes of the lower pair.

The projecting rear end of the regulator-arbor 17 mounts a crank-disk 19 carrying an eccentrically positioned screw-stud 20 passing through an inclined, converting-slot 21 in the outer upper corner of a regulator-lever 22 pivoted upon the right-hand end of the 70 plate 10 by means of a screw-stud 23. The said lever is also furnished with a horizontal converting-slot 24, likewise adapted to receive the screw-stud 20, and located below and toward the center of the movement with 75 respect to the upper slot 21 aforesaid. The inner end of the said lever 22 is furnished with a split-stud 26, from which the pendulum-rod (not shown) is suspended by its spring-end 27. The projecting forward end 80 of the arbor 17 is shown as squared for its provision with an operating-pointer, by which it is manually turned. This pointer, which is not shown, may be of any approved design. By turning the arbor 17, the lever 85 22 is swung on its screw-stud 23 so as to raise or lower the stud 26 and hence the pendulum-rod, whereby the clock is regulated.

The projecting rear end of the chime-cut-out-arbor 18 mounts a crank-disk 25 carrying an eccentrically placed screw-stud 28 passing through a vertical converting-slot 29 in the upper portion of a chime-cut-out-lever 30 secured to the inner end of a sleeve 31 rocking upon a stud 32 and provided at 95 its outer end with a cut-out finger 33 bearing upon the respective hammer-tails 34. The lever 30 is also provided with a vertical converting-slot 35, corresponding to the slot 29 but located below the same and inward, toward the center of the movement. If desired, the chime-cut-out-lever 30 may be used to cut out a strike-mechanism just as well as a chime-mechanism. The forward end of the arbor 18 is also squared for the 105 application of an operating pointer (not shown) by which it is manually turned as required.

For locating the arbors 17 and 18 to correspond to the different positions of the converting-slots 21 and 24, in the lever 22, and the slots 29 and 35, in the lever 30, the rear 5 and front bridges 10 and 11 are each provided, as described, with two pairs of mounting-holes 15, as already described and as shown in Fig. 4.

When my improved movement is assembled for use with a dial such as 36, in which the holes for the arbors 17 and 18 are located at a relatively long distance from the center-arbor hole of the dial, the said arbors 17 and 18 are mounted in the upper holes 15 of 10 the plates, as shown in Figs. 1 and 2. The stud 20 then operates in the inclined converting-slot 21 of the lever 22, while the stud 28 operates in the upper converting-slot 29 of the lever 30.

20 Now without any change in the movement, all that it is necessary to do to convert it for use with a relatively smaller dial, such as 37, in which the holes for the regulator-arbor and the chime-cut-out-arbor are located relatively nearer the center arbor-hole, is to 25 mount the arbors 17 and 18 in the lower holes 15 of the plates 10 and 11, and to pass the eccentric-studs 20 and 28 through the converting-slots 24 and 35 of the respective 30 levers 22 and 30. I am thus enabled to make one movement answer for dials of two different lay-outs, *i. e.*, of two different spacings of the holes for the center arbor and the regulator- and chime-cut-out-arbors.

35 I claim:

1. In a clock-movement, the combination with the movement-plates thereof, of two auxiliary plates respectively applied to the upper portions thereof and having a plurality of bearings, regulator- and cut-out-arbors mounted in the said bearings, levers connected with one of the said plates and 40 adapted to be operably connected respectively with the said arbors, wherever the 45 same are mounted in the auxiliary plates,

and means for connecting the said levers with parts of the clock-movement.

2. In a clock-movement, the combination with the movement-plates thereof, of auxiliary plates secured to the upper portions 50 of the respective movement-plates, and provided with a pair of upper bearings and a pair of lower bearings, the bearings of the lower pair being closer together than the bearings of the upper pair, a regulator- 55 arbor and a cut-out arbor mounted in the bearings of either one pair or the other, levers pivotally mounted upon one of the said plates and each provided with two converting-slots, eccentric connection between 60 the said arbors and the said slots, and means connecting the said levers with parts of the clock-movement.

3. In a clock-movement, the combination with the front and rear movement-plates 65 thereof, of auxiliary plates respectively applied to the upper portions of the movement-plates and each having a pair of upper bearings and a pair of lower bearings, of which the bearings of the lower pair are located closer together than the bearings of the upper pair, a regulator-arbor and a cut-out-arbor mounted in the bearings of one pair or the other, a crank-disk mounted upon 70 each of the said arbors and carrying a screw-stud, levers pivotally mounted upon one of the said plates and each provided with two converting-slots, the upper slots of the said levers being spaced apart more than the 75 lower slots thereof, and the said slots receiving the screw-studs of the crank-disks; and means for connecting the said levers with parts of the clock-movement.

In testimony whereof, I have signed this specification in the presence of two subscribing 85 witnesses.

FREDERICK WEHINGER.
